CLAIM

The ornamental design for a tool for use in plugging a cylindrical pipe, as shown and described.

DESCRIPTION

FIG. 1 is a right perspective view of a tool for use in plugging a cylindrical pipe showing my new design;

FIG. 2 is a left side view thereof;

FIG. 3 is a left side view showing the tool in retracted condition thereof;

FIG. 4 is a top plan view thereof; and

FIG. 5 is a rear view thereof.
